UNITED STATES PATENT OFFICE.

LACLEDE J. HOWARD, OF ST. LOUIS, MISSOURI.

DESIGN FOR A FIRE-PLUG BOX.

SPECIFICATION forming part of Design No. 30,738, dated May 9, 1899.

Application filed April 14, 1899. Serial No. 713,056. Term of patent 7 years.

To all whom it may concern:

Be it known that I, LACLEDE J. HOWARD, a citizen of the United States, residing at St. Louis, in the State of Missouri, have invented and produced a new and original Design for Fire-Plug Boxes, of which the following is a specification, reference being had to the accompanying drawings, forming part thereof.

Figure 1 is a top plan of a street fire-plug box, showing my new design; Fig. 2, a side elevation thereof, and Fig. 3 a vertical section through the box on line 3-3 in Fig. 1.

As shown in the drawings, the leading or material feature of my design consists in a six-sided fire-plug box A, having its sides or walls 1 arranged together hexagonally and

inclined inward toward each other from the base 2 upward, or, in other words, in the form of the frustum of a pyramid, the butting edges of the sides 1 being radial to the axis of the frustum and their top and bottom edges horizontal and flush with each other.

Having described my invention, what I claim as new, and desire to secure by Letters Patent, is—

The design for a fire-plug box, as herein shown and described.

LACLEDE J. HOWARD.
